UNITED STATES PATENT OFFICE.

EDWARD SLADE, OF NEWTON, AND JOHN S. STONE, OF BOSTON, ASSIGNORS
TO THE AMERICAN BELL TELEPHONE COMPANY, OF BOSTON, MASSA-
CHUSETTS.

TELEPHONE-CIRCUIT.

SPECIFICATION forming part of Letters Patent No. 553,179, dated January 14, 1896.

Application filed July 12, 1895. Serial No. 555,734. (No model.)

To all whom it may concern:

Be it known that we, EDWARD SLADE, residing at Newton, in the county of Middlesex, and JOHN S. STONE, residing at Boston, in the 5 county of Suffolk, State of Massachusetts, have invented certain Improvements in Telephone-Circuits, of which the following is a specification.

In systems of centralized or common current 10 rent-supply for telephone-exchange circuits, wherein the battery or other source of supply is placed directly in the main-line circuit, the said source is usually introduced into the subscriber's circuit with the operator's telephone by the insertion of a connecting-plug into the socket of a calling-subscriber's line for the purpose of answering the call. This sudden introduction into the circuit of a considerable electromotive force and current produces 15 in the subscriber's receiving-telephone a harsh rasping noise or click which most disagreeably and unpleasantly affects the ear of the user. In some systems of this class a battery of like magnitude to the talking-battery 20 is normally connected with the sub-station circuit for the production therein of a signaling-current; and in such systems the said disagreeable click is accentuated, because it is due to two distinct but rapidly succeeding 25 causes—viz., the sudden break of the original or signaling battery-circuit, and the sudden make of the working or talking battery circuit—and though two clicks really are made in the subscriber's telephone the second follows 30 so closely upon the first that to the subscriber's ear the effect is that of a single but prolonged sharp and unpleasant rasping noise.

The object of our invention is to prevent 35 or overcome this disagreeable click, which is heard by the subscriber as the operator plugs into the circuit; and this object is attained by providing that the electromotive force required for transmitter-supply shall be connected 40 with the circuit before that employed for signaling is disconnected, so that momentarily the two electromotive forces are applied to the circuit in parallel with each other, and at no time therefore is the distribution of 45 potential through the circuit materially disturbed. Thus in carrying out our invention

as the answering-plug is inserted in the socket the transmitter or talking-battery is connected with the subscriber's circuit before the signaling-battery is withdrawn therefrom, 55 and as the said plug is pushed fully into the socket the signaling-battery is disconnected. By adopting this plan of operation the connection of the talking-battery adds nothing to the difference of potential existing between 60 the terminals of the circuit, nor does the subsequent withdrawal of the signaling-battery deduct anything therefrom.

The signaling and talking generators should be substantially alike in power and must be 65 so connected that the currents they send to line shall be of like direction. This requirement permits of the use of a single generator for both purposes, and the invention therefore includes apparatus and circuit connections 70 whereby such a single generator may conveniently be so employed. This practice is in the majority of cases preferable, and can be carried out by providing the said generator with distinct sets of terminals 75 controlled by suitable switch devices, one set forming a signal-extension circuit or loop connected normally with the main-circuit terminals to maintain the resting or signaling instrument circuit and the other forming a telephone-circuit through the central-station telephones, being so placed and arranged that by the operation of the switch devices they may be connected with the main circuit in place 80 of the first set to establish the talking-circuit, 85 and vice versa, the said switch devices being so constructed that in making such transfer in either direction the circuit of the generator must be established through the second path before it is broken through the first. 90

Any of the well-known forms of switch may of course be employed in making the necessary circuit changes; but the plug-and-socket type, being in general use, is the form we employ in illustrating our invention, the socket 95 or spring-jack being constructed to contain the main-circuit terminals and one set of the generator-terminals, while the other set of generator-terminals, forming a loop through the transmitter, are mounted on the plug portion of the switch. 100

More specifically, the plug-socket or spring-

jack in which the invention is embodied, in addition to two innersprings forming the normal-circuit terminals and pressing while the circuit is at rest upon the terminals of the 5 signaling-generator, has two auxiliary contact-springs forming branch terminals of the two ends of the line-circuit, respectively, and projecting toward the front opening of the said socket. The connecting-plug is so modified that its rounded tip is made non-conducting, and it is constructed with two sleeve-conductors representing respectively the two conductors of the operator's answering-telephone and transmitter current generator, the said 10 sleeve-conductors being insulated from one another and adapted to register with the two auxiliary or branch socket-springs, and thus to continue the line-circuit through the transmitter-battery as soon as the plug is inserted, 15 while when the plug is pushed fully into the socket its rounded tip is enabled to lift the inner spring-terminals from their resting-contacts and thereby disconnect the normal signaling-generator.

25 In the drawings, Figure 1 is a diagram representing a circuit arranged on the old plan and involving the defect we seek to remedy. Figs. 2 and 3 are diagrams of a similar circuit embodying our invention and respectively 30 showing the connections as they are, first, when the plug is partly inserted, and, second, when the plug is pushed fully into its socket.

Similar letters and figures of reference in the several views represent similar parts.

35 C represents a subscriber's-telephone circuit having two line-conductors L and L² extending between a sub-station A and a central station B. It is shown as being provided at the sub-station with the subscriber's automatic hook-switch N, a receiving-telephone T² and transmitter M², and at the central station with a plug-socket D containing the spring-jack connections J and a normal extension-circuit b, comprising the calling appliance or 40 annunciator a and the signaling-generator S, which impresses upon the circuit a definite electromotive force, so that as soon as the circuit is closed at the sub-station in the usual way by removing the telephone from the hook 45 the signaling-current may flow in the circuit and operate the annunciator a.

M is the transmitter and T the receiving-telephone of the operator at the central station B, and these are included, together with 50 the generator of transmitting-current, in a normally-open station-circuit or extension-loop d, the two ends of which terminate in contact-surfaces p² and p³ of the connecting-plug P, so that when a call comes in from the 55 subscriber, manifesting itself by the fall of the annunciator-shutter, and is answered by inserting the plug P in the socket D, the contact-surfaces of the plug will register with the contact-springs of the jack J, and the 60 main circuit C and the extension-loop d will be joined up into a single talking-circuit, including the telephones at both stations and

the transmitter-generator S. The plug, in forming the new circuit through the operator's telephones and transmitter current generator, is also adapted to break the circuit through the signaling-battery and annunciator and to disconnect these appliances, which it does by means of its non-conducting rounded tip, which raises the terminal springs 75 2 and 3 from the fixed anvil-contacts e f.

In Fig. 1 the spring-jack connection J has the circuit-terminal springs 2 and 3 only, and these when at rest make contact with the signaling-generator terminals e and f; but on the 80 insertion of the plug they make contact with the conducting-surfaces p² and p³. The plug has a non-conducting handle portion, a conducting-tip p² of bulbous form, constituting the end of the conductor g of the answering-loop d, and a sleeve portion p³, forming the terminal of the other wire h thereof, the said 85 two conducting-surfaces being insulated from one another in the ordinary way by a ring and sleeve of non-conducting material.

90 When the plug P is first inserted in its socket D, its tip end raises the spring 2 from the point f, and thereby suddenly breaks the circuit of generator S. Being fully pushed in, the plug subsequently raises the other spring 95 3 from its resting-contact e, permits the said spring to make contact with its tip p², and establishes a second contact between the spring 2 and its sleeve-conductor p³, whereby the transmitter-current generator s replaces in 100 the circuit C the signaling-generator S. A sudden cessation of current necessarily occurs when the spring 2 is lifted from the point f, breaking the circuit of S, and a current is suddenly re-established when the two springs 105 2 and 3 make contact with the plug-surfaces, closing the circuit of s, and these abrupt changes produce a harsh and objectionable noise in the telephone T² at the sub-station, thus causing annoyance to the subscriber. 110 In Figs. 2 and 3 this fault is prevented. The spring-jack connection is provided with two auxiliary contact-springs 4 and 5, which are branched from the main conductors L and L², respectively, and project farther forward than 115 the original springs 2 and 3, which are now made both of the same length. The springs of both pairs are branch terminals of the circuit in parallel with each other, 2 and 3 being normally in contact with the signaling-battery terminals e and f and 4 and 5 being normally discontinuous branches.

120 The plug P is modified in structure, the bulbous tip p being made non-conducting, while the two conducting-surfaces p² and p³ are now both portions of the sleeve, albeit separated from one another electrically by the insulating-ring r. p² may connect with the wire g, and p³ with wire h.

125 The insertion of the plug P in its socket D, as shown in Fig. 2, to answer a call now first connects the two ends of the transmitter-current generator s, (represented by the plug-surfaces p² and p³), with the two ends of the

line-circuit C, as represented by the auxiliary springs 4 and 5, thus bringing into the circuit an additional generator parallel to the original one, and as the plug is forced 5 fully into the socket then disconnects the said original generator S by bringing its non-conducting bulbous tip p between the ends of the inner spring-terminals 2 and 3, thus separating them from their respective resting-contacts e and f, which form the terminals of the said generator.

As already indicated, the preferred arrangement in practice is to employ a single generator, such as a battery, to furnish both 10 signaling and talking currents, and this is indicated where in Fig. 2 the battery S is shown as being connected with the switch-plug surface-contacts by the conductors x y, (represented by dotted lines,) which unite 15 with the poles of the said battery at the points v and w and with the terminal wires g h of the telephone-loop d at the points m and n. Since in this operation the signaling-generator is not disconnected from the line until 20 the transmitter-generator is placed by its side in the line-circuit, its disconnection when effected produces no change in the electrical condition of the main circuit, and there is no noise in the subscriber's receiver. For 25 the same reason no click is produced in the subscriber's telephone when the plug is withdrawn from the socket, the signaling-generator being in that case connected with the circuit before the transmitter-generator is 30 disconnected therefrom.

The signaling and talking generators should be substantially alike in power, and must be so connected that the currents they send to line shall be of like direction.

40 We claim as our invention—

1. The combination of a telephone exchange circuit extending between a substation and a central station, and serving for the transmission of both signals and conversation; a 45 signaling current generator normally in circuit therewith; and a transmitter current generator adapted for connection therewith during the transmission of speech; with a switching device, such as a plug, controlling 50 terminals of said transmitter current generator and adapted to connect the same with said exchange circuit and subsequently to disconnect the signaling generator therefrom, substantially as described.

2. The combination of a main telephone circuit extending between a central and a substation; a signal extension circuit or loop at the former station containing a battery, and having its terminals normally united to the terminals of said main circuit to complete the 55 same through signaling instruments; a telephone circuit extension containing the same or equivalent battery and the central station transmitter, normally detached from but adapted to connect with the said main circuit, 60 and to form therewith a conversation circuit through the said transmitter; and switch devices controlling the terminals of the main and extension circuits, and adapted to transfer the connection of the main line from either 65 extension to the other, and in each transfer to close the circuit of the battery through the 70 second before breaking it through the first.

3. In a system of common or centralized battery telephone circuits, the combination 75 of a main telephone circuit extending between a substation and a central station, having at the former a receiving telephone, and terminating at the latter in a plug socket containing a normal and an auxiliary contact 80 spring, forming alternative terminals for each end of the circuit; a signal current battery normally connected with the said main circuit through the normal terminal springs thereof; a transmitter current battery adapted 85 to replace said signaling current battery in the circuit during the operation of the telephone; and a switch plug controlling the terminals of said transmitter battery and adapted for insertion in the said socket and thereupon to first connect the said battery terminals with the auxiliary springs of the main 90 circuit, and then sever the normal springs of the main circuit from the terminals of the signaling current battery, whereby the batteries may be exchanged on the insertion and withdrawal of said plug, without producing 95 a disturbing noise in the substation telephone, substantially as described.

In testimony whereof we have signed our 100 names to this specification, in the presence of two subscribing witnesses, this 3d day of July, 1895.
